UNITED STATES PATENT OFFICE.

FREDERICK L. RAY, OF LOUISVILLE, KENTUCKY.

FEED-WATER REGULATOR.

1,171,643.

Specification of Letters Patent. Patented Feb. 15, 1916.

Application filed September 9, 1914. Serial No. 860,941.

To all whom it may concern:

Be it known that I, FREDERICK L. RAY, a citizen of the United States, residing in Louisville, county of Jefferson, and State of Kentucky, have invented new and useful Improvements in Feed-Water Regulators, of which the following is a specification.

My invention relates to automatic feed water regulators and its object is to provide a device affording a continuous and automatic feed of water into a boiler in proportion to the evaporation, to provide a device which will accomplish this result without consuming any steam or water and without suffering interference from fluctuations in pressure, either in the boiler or in the source of water supply.

My device is also applicable for the maintaining of a constant level in other liquid-containers.

I accomplish these results by and through the mechanism illustrated in the accompanying drawings, in which—

Figure 1 is a vertical section of the entire apparatus, Fig. 2 is a longitudinal section through the valve-bushing B^1 ; Fig. 3 is a transverse section of the same; Fig. 4 is a section through the line marked $Z Z$ in Fig. 1, and Fig. 5 is a top view.

Similar letters refer to similar parts throughout the several views.

A^1 is a casting forming a float chamber at the bottom and a valve chamber at the top. It is closed at the bottom with a head A^2 . A^3 and A^4 are pipes leading from the interior of the said float chamber into the boiler E , and are connected with the boiler at a place such that the mean water level of the boiler will be about opposite the middle of the float chamber.

A^5 is a water gage which is connected at A^6 and A^7 with the casting A^1 and the float chamber within.

At the points A^8 , A^9 and A^{10} gage cocks are attached to the casting A^1 , which is perforated so that the cocks when in position will be in communication with the chamber within.

In the upper part of the casting A^1 , forming a valve casing, there is a cylindrical opening, which has annular grooves A^{11} and A^{12} cut in its wall. One of these grooves is adjacent to an inlet opening A^{13} , the other opposite an outlet opening A^{14} , the

groove A^{14} extends over to the edge of the casting. A head A^{15} is provided to close in the cylindrical space before mentioned. A sleeve or bushing B^1 in the form of a tube or pipe fits inside the cylindrical space and is provided with two sets of ports or windows, B^2 , B^3 as shown in Figs. 2 and 3. When the sleeve is in position one set B^2 of these ports lies opposite the annular groove A^{12} which is adjacent to the inlet A^{13} , and the other set of ports B^3 lies in communication with the annular groove which is adjacent to the outlet A^{14} .

The inner cylindrical surface of the sleeve or bushing B^1 forms the inner surface of the valve chamber structure. One wall of the cylindrical opening in the casting A^1 is a plate of metal which separates the float chamber from the valve chamber, and this wall or plate is pierced at A^{16} and the valve stem C^1 is movable therethrough, a bushing being provided to prevent leakage.

Attached to the valve stem C^1 is a piston C^2 . As shown in the drawing this piston C^2 is elongated and has ends of such diameter as to fit snugly the inside of the sleeve or bushing B^1 . It is provided at the end nearest the opening A^{16} with water grooves C^3 to hinder leakage. Intermediate between the ends of the piston the external diameter of the piston is reduced so that an annular space is left between the inner walls of the sleeve and that portion of the piston having the reduced diameter. The piston is tubular, the outer structure of the piston being attached to the stem C^1 by means of a web at each end. The space between the piston C^2 and the head A^{15} communicates with the outlet and the outlet ports, a space being left between said head A^{15} and the end of the sleeve or bushing B^1 . The piston is movable parallel with the axis of the cylindrical bushing B^1 , between the limits fixed by the head A^{15} and the other end of casing wall, and the outlet ports B^3 are so placed that in some positions of the piston they are in communication with the annular space between the inner cylindrical wall of the piston chamber (being the inner surface of the bushing B^1) and that portion of the piston-surface which is of less diameter, and in other positions they are cut off from said space by the end of the piston. The outlet ports are at all times, however, in communi-

cation with the outlet opening in the casting A¹ and also with the groove E³ and the space adjacent to the head A¹⁵. A pipe A¹⁴ communicates between the outlet opening and the boiler.

5 A float D¹ is provided in the float chamber and is adapted to rise and fall as the level of water in the float chamber and boiler rises and falls. In the form shown it 10 is spherical and of hollow metal. A float rod D² is attached to the float, and there is pivoted to the extremity of said float rod a bell crank pivoted at D⁴, the other extremity of the crank being pivoted to the valve stem 15 C¹. The bell crank D³ is bored at D⁴, so as to work on a pin D⁵, one end of which is fitted into a socket A²⁴ in the casting A¹, the other end passing through a ring A²⁰ and a hollow nut A²¹ inserted in a suitable opening 20 in the casting A¹. By means of this structure renewal of worn parts is made convenient. The casting A¹ is provided with a head A¹⁷ which makes tight the upper part of the float chamber and in this head a testing device is provided, consisting of a plug 25 A¹⁸ through which a threaded stem A¹⁹ can be screwed in so as to move the valve stem independently of movements of the float.

30 The operation of the apparatus is as follows: When the water lever falls in the boiler, it also falls in the float chamber, causing the float to move downward. This downward motion of the float, transmitted through the float-rod and bell crank, causes 35 a thrust in the valve stem and so causes a movement of the piston. The annular space around the piston being at all positions in communication with the inlet ports B² and inlet A¹³, all of these spaces are 40 filled with water when the valve is closed and the float is at the highest level; when the valve is pushed away from the seat, the outer end of the piston is pushed past the outlet ports, which opens up a communication 45 between the annular space around the piston, filled with water, and the outlet ports B³ which lead to the outlet A¹⁴. The water flows through this space and into the outlet ports and thence into the pipe leading 50 into the boiler. When it reaches the boiler it tends to raise the water level and thus to raise the float. The rising of the float, by means of the float rod and bell crank, operates to draw the piston back toward its seat 55 and thus close communication between the outlet ports and the space around the piston. It is evident that a slight difference in the level opens the valve slightly and that a large difference in level opens it wider so 60 that the operation of the valve adjusts itself to the rapidity of the evaporation or change in level. One of the objections to most forms of feed water regulators is that their action is interfered with by sudden fluctuations 65 in pressure in the boiler and also by

sudden fluctuations in the supply pipe leading to the regulator, tending to throw the valve out of balance and interfering with its operation. The arrangement of outlet and inlet which appears in my device obviates all difficulty of this character and produces a valve which is balanced as against fluctuations of both kinds and is also so balanced as to require a minimum of force to operate it. In view of the fact that the piston is 75 tubular and that the closed spaces between piston and the ends of the cylinder are in communication with the outlet ports and through them with the boiler itself, no force is required of the float, in order to operate 80 the valve, except that required by friction and by the slight difference in pressure due to the area of the valve stem. Furthermore the fact that the water comes through the inlet and surrounds the piston prevents any 85 unequal pressure on the same or any undue pressure from above.

In regulators employing piston valves, so designed that the space at the end of the piston is in communication and under the 90 same pressure as that existing in the inlet pipe, the amount of force required to move the valve will vary with the amount of pressure in said inlet pipe, and this trouble interferes with the usefulness of the valve. 95 In view of the fact that it is sometimes impossible to avoid such variations at the inlet it will be evident that my structure presents an important advance over devices designed in that way. No change in the buoyant 100 force of the float is required in my device even though the head in the inlet pipe should be greatly multiplied.

It will be noticed that the tubular interior of the piston is in communication with the 105 outlet-passage and thus with the interior of the boiler at all positions of the piston, and also with the closed spaces at each end of the piston between the ends of the piston and the walls of the valve chamber. This 110 balances the piston perfectly, because the pressure on the ends of the piston is the same. In types where one end of the piston is open to the atmosphere, it is evident that 115 there cannot be a complete balance for both ends of the piston. The sleeve or bushing employed renders it possible to renew certain of the parts of the machine subject to wear without extensive renewal, and renders the machine easily cleaned and repaired. The use of the bushing or sleeve, and the arrangement of perforations as described, is designed to perform a similar 120 function.

125 The testing device is utilized for the purpose of finding out immediately whether the piston is in working order. By screwing it in, the valve is immediately opened, irrespective of the position of the float, and water will flow through the valve. After test- 130

ing, the testing stem is screwed out again and the valve is again subject to movements of the float.

This device also provides a means by which the passage from the source of supply to the boiler can be opened and held open, thereby cutting the regulating apparatus out of service when desired.

Three annular grooves B^4 are cut in the bushing B , to take care of scale and sediment, which can accumulate in the groove to a considerable extent without interfering with the piston. The edge of the grooves also acts as a cutting edge which tends to clean the piston of adhering scale. The two outermost grooves are located where the piston would be most likely to stick if scale has accumulated; that is, when the valve is wide open, the grooves are adjacent to the close-fitting portion of the piston. This diminishes the danger of such sticking, and diminishes friction at that part of the stroke when friction counts for most—when the piston is starting on its return stroke. The grooves at this position prevent the limitation of the piston's movement through the formation and growth of a ridge of scale next to the extreme position of the piston. The grooves are located so that when the piston is wide open, the outer edge of the close fitting portion of the piston is opposite the groove.

I claim as new and desire to protect by Letters Patent the following:

- 35 1. In a boiler feed water regulator, a float, parts forming a float chamber, a tubular piston having a stem, parts connecting said float and said stem, parts forming a piston chamber of cylindrical interior, having inlet and outlet openings and ports therein, a plate separating said float chamber from said piston chamber, said plate being pierced so that the piston stem is movable therethrough, and a head closing the opposite end of said piston chamber; the said piston having a cylindrical outer surface, which near each end of the piston is of such diameter as to fit the cylindrical interior of the cylinder-chamber, but which is of less diameter between said end portions, the limits of motion of said piston being such that the inlet port is always in communication with the annular space between the inner cylindrical wall of the piston chamber and that portion of the piston surface which is of less diameter, but the outlet is in certain positions in communication with said annular space, and in other positions is cut off by the end of the piston, the space between the before mentioned separating plate and the nearest end of the piston being connected with the space between the other end of the piston and the head before mentioned by

  - 120
- the tubular interior of the piston, the space between the before mentioned head and the end of the piston nearest to it being at all positions in communication with the outlet port above mentioned.
2. In a feed water regulator, a float designed to rise and fall with the level of water in the boiler, parts forming a valve casting into which lead openings designed for inlet and outlet, a bushing having two sets of perforations, so placed that one set is adjacent to the inlet, and the other adjacent to the outlet, a tubular piston movable within fixed limits in said bushing and having its outer surface so formed that its ends fit closely to the bushing but leave an annular space intermediate between said ends, between the walls of said chamber and the surface of said piston, the said perforations being further so placed that said annular space in certain positions of the piston is in communication with both sets of perforations and in other positions is in communication only with the inlet set of perforations, all in combination with means for causing said piston to go forward or back according as the float rises or falls, parts forming a passage leading from the outlet chamber to the boiler, the outlet opening being so extended by a groove in the inner surface of the casing, and the bushing being so placed in the opening which receives it that the outlet opening directly communicates with the space adjacent to the head.
3. In a feed water regulator, a float designed to rise and fall with the level of water in the boiler, parts forming a valve casting into which lead openings designed for inlet and outlet, a bushing having two sets of perforations, so placed that one set is adjacent to the inlet, and the other adjacent to the outlet, a piston movable within fixed limits in said bushing and having its outer surface so formed that its ends fit closely to the bushing but leave an annular space between said ends and between the walls of said chamber and the surface of said piston, the said perforations being further so placed that said annular space in certain positions of the piston is in communication with both sets of perforations and in other positions is in communication only with the inlet set of perforations, all in combination with means for causing said piston to go forward or back according as the float rises or falls, and parts forming a passage leading from the outlet chamber to the boiler, the bushing having annular interior grooves with sharp edges, substantially as described.
